CLAIM

USPC **D8/63**

The ornamental design for a power sharpener, as shown and described.

(58) **Field of Classification Search**

DESCRIPTION

USPC D8/63, 91, 92, 93

FIG. 1 is a perspective view of a power sharpener showing the new design.

CPC B24B 3/54; B24B 3/36; B24B 3/58; B24B 3/00; B24B 23/06; B24B 23/08; B24B 15/00; B24B 15/06; B24B 15/063; B24B 15/08

FIG. 2 is a left elevational view of the power sharpener of FIG. 1.

See application file for complete search history.

FIG. 3 is a right elevational view of the power sharpener of FIG. 1.

(56)

References Cited

FIG. 4 is a top plan view of the power sharpener of FIG. 1.

U.S. PATENT DOCUMENTS

FIG. 5 is a bottom plan view of the power sharpener of FIG. 1.

324,139 A	8/1885	Mckaig
632,458 A	10/1899	Albert
1,568,869 A	1/1926	Boes
1,583,554 A	5/1926	Hoover
